(57) **CLAIM**

We claim an ornamental design for a gel applicator for magnetic resonance imaging, as shown and described.

DESCRIPTION

FIG. 1 is a front perspective view of the gel applicator for magnetic resonance imaging in accordance with an embodiment of the present design;

FIG. 2 is a top plan view of the gel applicator for magnetic resonance imaging of FIG. 1;

FIG. 3 is a side plan view of the gel applicator for magnetic resonance imaging of FIG. 1;

FIG. 4 is a rear elevation view of the gel applicator for magnetic resonance imaging of FIG. 1; and,

FIG. 5 is a front elevation view of the gel applicator for magnetic resonance imaging of FIG. 1.

In FIGS. 1-5, the features of the gel applicator for magnetic resonance imaging shown in phantom lines are for illustrative purposes only and do not constitute a part of the claimed design.
